MOLDING PRESS

August F. Toelke, Sun Prairie, Wis.

Application June 21, 1933, Serial No. 676,858

11 Claims. (Cl. 25—80)

This invention relates to molding presses primarily for use in the production of bricks and other ceramic articles, although the use thereof in compacting and molding other plastic or like materials into various shapes is also contemplated.

In presses for such purposes heretofore used, a rather gradual application of the compacting and molding pressures is ordinarily required to produce perfect blanks free from objectionable fissures or fractures which would otherwise be developed therein. This condition imposes a serious limitation upon the speed at which such presses may be economically operated and correspondingly curbs the production capacity thereof.

An object of the present invention is to provide an improved press for this purpose which will reliably produce perfect blanks at high speed operation. This I have accomplished by the production of a press in which the compacting and molding pressures are pneumatically applied in such manner as to utilize in full measure the characteristic resiliency of air or other gaseous medium under pressure.

Another object is to provide an improved automatic control for such presses especially suited for high speed press operation.

Presses for these purposes not infrequently include a rotary mold carrier, which requires periodic indexing, and a cooperating pressure plunger. Another object is to provide an improved means for automatically controlling and coordinating the indexing of the carrier and the reciprocation of the plunger, so as to reliably effect proper sequential operation thereof.

Other objects and advantages will appear, either expressed or implied, from the following description of a molding press embodying the present invention.

In the accompanying drawings:—

Figure 1 is a vertical sectional view, taken substantially along the line 1—1 of Fig. 2, of a molding press constructed in accordance with the present invention.

Fig. 2 is a vertical sectional view taken at right angles to the plane of the section of Fig. 1.

Fig. 3 is a fragmentary sectional view illustrating on a somewhat larger scale a part of the control mechanism shown in Fig. 1.

Fig. 4 is a sectional view, also on a larger scale, of another portion of the control mechanism shown in Fig. 1.

Fig. 5 is a fragmentary sectional view on the line 5—5 of Fig. 2.

Fig. 6 is a top elevation of a metering plate and its actuating mechanism.

The molding press selected for illustration includes a main cylinder 10, supporting a smaller pull-back cylinder 11 aligned therewith, the main cylinder being mounted upon a plate 12, anchored to an appropriate supporting frame 13. A relatively large single-acting piston 14 in the cylinder 10 serves to drive a plunger 15 downwardly on a pressure stroke, the plunger being returned by a relatively small single-acting piston 16, working in the cylinder 11 and connected to the piston 14 by a rod 17.

The pistons 14 and 16 are actuated by air or other resilient pressure fluid, supplied through a pipe or conduit 18 under the control of an appropriate valve 19.

The control valve shown is of a well known type involving a double-headed piston 20, which in its upper position admits pressure fluid from the pipe 18 to a passage 21, leading to the main cylinder 10, and which in its lower position admits pressure fluid from the pipe 18 to a passage 22 leading to the pull-back cylinder 11. In either position of the piston 20 the pressure fluid passes between the end heads thereof so that the same is always balanced as to pressure and its position is not disturbed thereby. When the piston 20 is in upper position the passage 22 from the pull-back cylinder is open to an exhaust port 23, and when in lower position the passage 21 from the main cylinder is free to exhaust through the upper open end 24 of the valve casing.

In this instance the valve 19 is controlled by a stop element 25 which coacts with a stem 26 depending from the valve piston 20. The valve piston is urged downwardly by gravity or otherwise. The element, shown at 25, is in the form of a plate mounted for lengthwise movement crosswise of the valve stem 26, and is provided with an opening 27 through which the stem 26 instantly projects whenever the opening 27 is caused to register therewith by a longitudinal shifting of the plate. This of course results in a prompt shifting of the valve piston 20 into its lower position.

The plate 25 is also mounted for movement in a direction longitudinally of the valve stem 26, and serves, by such movement, to lift the valve piston 20 into its upper position.

These two distinct movements of the plate 25 are made possible in this instance preferably by a mounting means which will now be described. One end of the plate 25 is supported by a rod 28, through a ball-and-socket joint 29, and at its

other end the plate is hingedly connected, as at 30, to the depending arm 31 of a bellcrank rockably supported upon a fixed horizontal pivot 32. The bellcrank 31 is actuated and controlled, in a 5 manner to be later explained, by a pull rod 33, extending loosely through the other horizontal arm 34 of the bellcrank, and provided with a stop nut 35, adjustable thereon.

An appropriate spring 36 urges the arm 31, and 10 consequently the plate 25, toward the left from the position of Fig. 1, so that the opening 27 is normally out of register with the valve stem 26, in which position the valve piston 20 is retained in the elevated position shown and the main cylinder 15 15 10 is exposed to fluid pressure.

Whenever the arm 31 is swung toward the right, against the spring 36, so as to shift the plate 25 into the Fig. 1 position, the valve stem 26 is free to pass through the opening 27, and the valve 20 piston 20 shifts instantaneously into its lower position, so that the pull-back cylinder 11 is then exposed to fluid pressure and the plunger 15 executes a return stroke.

Thereafter, by a pull on the rod 28, the outer 25 end of the plate 25 is lowered until the opening 27 therein clears the end of the stem 26, whereupon the plate 25 and arm 31 are shifted toward the left, by the spring 36, so as to reposition the outer end of the plate 25 beneath the stem 26. 30 Then by an upward thrust on the rod 28, the plate 25 and consequently the stem 26, are lifted and return the valve piston to its upper position. The main cylinder 10 is thus again exposed to fluid pressure and the plunger 15 starts down on its 35 next working stroke.

Movement of the arm 31 toward the left is preferably limited by suitable coating stops 37 and 38 on the bellcrank and its support, respectively, the arm 31 assuming this limiting position 40 substantially throughout the working stroke of the plunger 15, and reassuming that position when, during the up stroke, the plate 25 is lowered to clear the stem 26.

Appropriate means for operating and controlling the rods 28 and 33 will be fully described hereinafter.

The plunger 15 carries a die 39 which cooperates successively with a circular series of split dies 40 carried by a rotary mold drum 41. The halves 50 of each die 40 are hinged to individual die carriers 42, each guided for lengthwise reciprocation radially of the drum in appropriate sockets 43 formed in the periphery of the drum. Each carrier 42 is slotted to accommodate the curved tails 55 44 of the die halves, the tails cooperating with the individual sockets 43 to spread the die halves and thereby release the contained molded blank, whenever the carrier is projected outwardly, as indicated in Fig. 2.

60 The die carriers 42 are controlled by individual cross-heads 45, attached to the lower ends thereof and projecting through and guided by radial slots 46 provided in the web 47 of the mold drum. In their inner retracted positions the several carriers 42 rest against appropriate individual abutments 48 provided on the hub 49 of the drum.

The drum 41 is mounted for intermittent rotation about a horizontal axis beneath the plunger 15 and, in this instance, is supported by a shaft 70 50 which extends through the hub 49 and through appropriate hangers 51 depending rigidly from the supporting frame 13. Indexing of the drum is effected by suitable means, such as a dog 52, carried by a reciprocable rod 53, and cooperating 75 with successive notches 54 formed in the periphery

of the drum to actuate the same. The rod 53 is fluid actuated by a piston 55 working in a cylinder 56 fixed to and depending from the plate 12.

Each indexing movement of the drum 41 is controlled and accurately limited by an index pin 57, mounted in a block 58 fixed to an auxiliary support 59, and cooperating with a series of holes 60 suitably arranged in the end of the drum. A spring 61 urges the pin 57 toward the drum, the pin being retractable by an appropriate lever 62, herein shown as a hand lever. The arrangement is such that when the pin 57 is retracted, by actuation of the lever 62, and the cylinder 56 energized, the drum is rotated by the dog 52, until the next hole 60 of the series registers with the pin 57, whereupon the pin snaps into that hole so as to prevent further rotation of the drum and to accurately position the same.

By each indexing movement of the drum a new die 40 in the upper part of the drum is brought into accurate alignment beneath the plunger die 39, and also a new die 40 in the lower part of the drum is brought into the blank ejecting position of Fig. 1.

In the machine shown the several dies 40 and 25 their carriers 42 are actuated and controlled in 30 their movements radially of the drum by mechanism carried by and movable with the plunger 15. This mechanism includes a pair of bars 63 hingedly mounted, as at 64, on the opposite ends 35 of a cross-head 65 secured to and movable with the plunger 15. The bars 63 extend downwardly from the ends of cross-head 65 adjacent the ends 40 of the drum 41, and each is provided intermediate its ends with a cam lug 66 for coaction with continuous cam surfaces 67 formed internally of the drum ends. Each bar 63 is also shaped at its lower end to form a catch 68 adapted to engage beneath an end of a carrier cross-head 45 and to provide a cam surface 69. Springs 70 yieldably draw the 45 bars 63 toward each other.

The arrangement is such that, during each up stroke of the plunger 15, the aligned carrier 42 and its cross-head 45 are lifted by the catches 68 until the bars 63 are forced outwardly by the 45 spreading action of the cam lugs 66 against the cam surfaces 67, the bars being retained in this spread condition until, during the next down stroke, the lugs 66 pass the cam surfaces 67 and permit the catches 68 to engage beneath the ends 50 of the cross-head 45 of the next carrier 42 which has, in the meantime, been brought into alignment with the plunger 15.

The carrier actuating mechanism shown also includes a second pair of bars 71, fixed at their 55 upper ends to the plunger cross-head 65, and extending downwardly into the vicinity of those carriers 42 in the bottom side of the drum 41. Each of the bars 71 is forked, as at 72, at its upper end to accommodate the intermediate bar 63, and 60 yoke shaped, as at 73, intermediate its ends to accommodate the hub ends 74 of the drum. The lower end of each bar 71 is shaped to provide an oppositely tapered notched head 75 for interlocking engagement with an end of an adjacent 65 carrier cross-head 45.

The arrangement is such that during each up stroke of plunger 15 the bars 71 lift and thus retract the engaged carrier cross-head 45 substantially into contact with its cooperating abutment 70 48, and then after the drum 41 is indexed and during the next down stroke of the plunger 15, the heads 75 engage the cross-head 45 of the newly positioned carrier 42 and force the same downwardly into the projected blank ejecting position 75

shown in Fig. 1. The bars 71 are sufficiently resilient to permit the heads 75 to snap over and into interlocking engagement with the ends of the aligned carrier cross-head 45 during this downward movement thereof with the plunger 15.

During the intermittent rotation or indexing of the drum 41 clockwise (Fig. 1), the several dies 40, having been projected into blank ejecting position and having been thereafter retracted, are carried upwardly by the drum so as to position them successively beneath the plunger die 39, and during this upward travel, each die 40 receives a fresh supply of material from an appropriate reservoir or hopper 76.

The reservoir shown is in the form of an open bottomed cylinder which rests upon a metering disk 77 rotatably secured to the plate 12 by means of a center stud 78 screwed into the plate. Arms 79 depending from the reservoir 76 engage the plate 12 and frame 13 to position the reservoir and to retain the same against rotation with the disk 77. The disk 77 is provided with a circular series of holes 80, open to the contents of the reservoir, and each of a size to contain a properly measured supply of material for one of the dies 40. These holes 80 are arranged to pass successively over a discharge opening 81, formed in the plate 12, and beneath a stationary plate 82 in the bottom of the reservoir. As the disk 77 rotates, the plate 82 serves to sever the charge of material in the adjacent hole 80 from the contents of the reservoir, so as to permit that charge to discharge through the opening 81 into a chute 83 through which it is conducted to one of the dies 40 in the drum.

The metering disk 77 is intermittently rotated or indexed by appropriate means, such as a ratchet pawl 84, cooperating with notches 85 in the periphery of the disk, and supported and actuated by an oscillating lever 86. The lever 86 is intermittently actuated preferably from a tail rod 87 on the piston 16 through appropriate connections (not shown) including the link 88.

Provision is made in the machine shown for automatically actuating and controlling the index pin 57, the indexing cylinder 56, and the rods 28 and 33 which control the actuation of the plunger 15, so as to assure operation of the several parts of the machine in proper sequence. This control mechanism will now be described.

The index pin actuating lever 62 is fixed to a rock shaft 89, journaled in the block 58, and carrying a crank arm 90 and a crank arm 91 at the opposite ends thereof. Arm 91 is connected to the rod 28. Arm 90 is connected, through a link 92, with a piston 93, working in a cylinder 94, supported by the plate 12.

The cylinder 94 is energized through a pipe 95, under the control of an auxiliary valve 96, which in turn is controlled by the plunger 15 in a manner to be later explained.

The indexing cylinder 56 is energized through a pipe 97 under control of a second auxiliary valve 98, which in turn is controlled by the lever 62.

The auxiliary valves 96 and 98 are similarly constructed. Each includes a poppet valve 99, which controls communication between a pressure chamber 100 and a feed chamber 101, the valve element 99 having a stem 102 loosely engaged within an actuating member 103, which functions to control an exhaust port 104 and also to displace the valve element 99 from its seat when said member 103 is forced inwardly, thereby to open communication between the chambers 100 and 101. The member 103 is provided with

an actuating stem 105 which projects outwardly from the end of the valve housing. The chamber 100 is always exposed to fluid pressure through a pipe 106.

The valve 96 is mounted upon an auxiliary support 107 in such position that its stem 105 projects into the path of a trip element 108, carried by the plunger cross-head 65. The trip element 108 is rockably mounted, as at 109, and so arranged as to force the stem 105 inwardly at a predetermined point in the upward travel of the plunger 15, but it is free to rock upwardly so as to pass the stem 105, without disturbing the same during the down stroke of the plunger. The pipe 95, leading to the cylinder 94, communicates with the chamber 101.

The valve 98 is mounted upon an auxiliary support 110 in such position that its stem 105 is actuated by an enlargement 111 on the lever 62, whenever the lever 62 is actuated to withdraw the index pin 57. The pipe 97, leading to the indexing cylinder 56, communicates with the chamber 101 of this valve.

The rod 33 is connected at its lower end to an arm 112 rigidly connected with one of the bars 63, so that when the cam lug 66 thereon clears the cam surface 67 of the drum, during the down stroke of the plunger 15, permitting the bar 63 to swing inwardly, the arm 112 is actuated to pull the rod 33 and thereby reverse the valve 19 in the manner above explained.

The several parts of the control mechanism coact to effect operation of the machine in the following manner. In the illustrated positions of the parts, the plunger 15 has completed its downward working stroke. The plunger die 39 has completed the compacting and molding of the charge of material in the aligned die 40, and the carrier 42 of the opposite lower die 40 has been projected by the bars 71 so as to discharge a molded blank onto an appropriate conveyor 115 disposed therebeneath. Also the bars 63 have swung inwardly into engagement with the cross-head 45 of the upper aligned die carrier 42, and the rod 33 has been actuated so that the plate 25 has been shifted to register the hole 27 with the stem 26 of the main valve 19. Instantly thereafter the valve piston 20 moves downwardly, projecting the valve stem 26 through the hole 27 and the press plunger 15 begins an upward or return stroke.

During this return stroke, the projected lower die carrier 42 is lifted and thus retracted by the bars 71; and the upper die carrier 42, containing the freshly molded blank, is lifted by the bars 63, so that it travels upwardly with the plunger die 39 until that die has cleared the co-acting socket 43, and thereafter the bars 63, spread by the action of lug 66 against the cams 67, release the carrier and permit the plunger die 39 to complete its upward travel alone. By this arrangement the plunger die 39 is not separated from the die 40 until they have cleared the socket 43, thereby avoiding a vacuum effect which would spoil the blank if it were attempted to separate those dies while in the socket 43.

At a predetermined point in the return stroke of the plunger 15, the trip element 108 strikes the stem 105 of valve 96 and forces the member 103 thereof inwardly, to close the exhaust port 104, and to unseat the element 99 so as to connect pipe 95 with the pressure pipe 106. The cylinder 94 is thus energized to actuate the lever 62 and thereby withdraw the index pin 57 from engagement with the drum 41.

The lever 62, thus actuated, strikes the stem 105 of valve 98 and forces the member 103 thereof inwardly, to close the exhaust port 104, and to unseat the element 99, so as to connect pipe 97 with the pressure pipe 106. The indexing cylinder 56 is thus energized to thereby rotate and index the drum 41. In the meantime the trip element 108 has cleared the stem 105 of valve 96, and the member 103 has again moved outwardly, thereby permitting the element 99 to reseat and reopening the exhaust port 104, and thereby deenergizing the cylinder 94. The index pin 57 is thus free to enter the next hole 60 in the drum and to thereby stop and accurately position the next die 15 40 beneath the plunger die 39.

At the time that the index pin 57 was withdrawn by the actuation of lever 62, this movement of the lever, transmitted through the crank arm 90, actuated the rod 28 and swung the plate 25 20 downwardly so that the hole 27 therein cleared the end of the valve stem 26. When this occurred, the plate 25 and arm 31 shifted to the left, under the action of the spring 36, thereby positioning the solid end of the plate 25 beneath the projected valve stem 26.

Thereafter, as the index pin 57 advances into the new hole 60 in the drum, the lever 62 is thereby actuated in such direction as to lift the crank arm 90 and thereby force the rod 28 and plate 25 upwardly. This action returns the valve piston 20 into the upper position shown, so as to energize the main cylinder 10 and thereby force the plunger 15 downwardly on its next working stroke.

35 During the down stroke of the plunger 15, the bars 71, carried by it, engage the cross-head 45 of the lowermost die carrier 42 and force it into the projected blank-ejecting position shown; and the plunger die 39 enters the aligned socket 43 40 and coacts with the uppermost die 40 to compact and mold the charge of material previously applied thereto. As the plunger 15 approaches the end of its down stroke, the lugs 66 clear the cams 67, so as to permit the bars 63 to swing inwardly, 45 and finally the latches 68 thereon swing into engagement beneath the ends of the carrier cross-head 45. The valve control plate 25 is shifted, through the arm 112 and rod 33 toward the Fig. 1 position by this inward swinging action of one 50 of the bars 63, but it is not until this swinging action is completed by actually engaging the catches 68 beneath the cross-head 45, that the plate 25 is shifted sufficiently to permit shifting of the valve piston 20 into its lower position.

55 Due to this arrangement, the control mechanism is ineffective to automatically reverse the motion of the plunger 15, to begin an upward return stroke, until the catches 68 are actually engaged beneath the crosshead 45, so that the engaged die 40 always moves with the plunger die 39 for a short distance on each stroke of the plunger.

Various changes may be made in the embodiment of the invention hereinabove specifically 65 described without departing from or sacrificing the advantages of the invention as defined in the appended claims.

I claim:—

1. In a molding press the combination of co- 70 acting molding dies, means for reciprocating one of said dies to effect a working stroke and a return stroke, separate means movable with said first named die for holding said dies against separation during an initial part of the return stroke 75 thereof, and means for releasing said holding

means to permit said dies to separate before completion of the return stroke.

2. In a molding press the combination of co- 5 acting molding dies, means for reciprocating one of said dies to effect a working stroke and a return stroke, a movable carrier for another of said dies, means movable with said first named die and engageable with said carrier to move the same with said first named die during a return stroke thereof, and means responsive to the engagement of said last named means with said carrier for automatically reversing the motion of said first named die at the end of a working stroke thereof.

3. In a molding press the combination of co- 15 acting molding dies, fluid means for reciprocating one of said dies to effect a working stroke and a return stroke, a movable carrier for another of said dies, means movable with said first named die and engageable with said carrier to actuate 20 the same, and means responsive to engagement of said last named means with said carrier for controlling said fluid means.

4. In a molding press the combination of co- 25 acting molding dies, fluid means for reciprocating one of said dies to effect a working stroke and a return stroke, valve mechanism for controlling said means, a movable carrier for another of said dies, means movable with said first named die and rockable into engagement with said carrier 30 to actuate the same during a part of the return stroke of said first named die, and means responsive to the rocking action of said last named means for controlling said valve mechanism to initiate a return stroke. 35

5. In a molding press the combination of co- 40 acting molding dies, fluid actuated reciprocating means for one of said dies effective to produce a working stroke and a return stroke, valve mechanism for controlling said means, a movable car- 45 rier for another of said dies, carrier actuating means movable with said first named die and rockable into engagement with said carrier at the end of each working stroke, means responsive to the rocking action of said last named means for shifting said valve mechanism to thereby initiate a return stroke, and means for disengaging said carrier actuating means at a predetermined point in said return stroke.

6. In a molding press the combination of co- 50 acting molding dies, resilient fluid pressure means for directly operating one of said dies to produce a working stroke and a return stroke and thereby effect compacting pressure therebetween, separate means for holding said dies 55 against separation at the end of a working stroke, and means for releasing said last named means to permit separation of said dies at a predetermined point in said return stroke.

7. In a molding press the combination of a 60 fluid actuated rotary carrier, a series of molding dies carried thereby and movable therein, a reciprocating molding die for coaction with said series of dies successively, fluid actuated means for actuating said reciprocating die, means actuated by and movable with said last named means for moving said dies in said carrier, and control means for effecting actuation of both of said fluid actuated means in predetermined sequence. 65

8. In a molding press the combination of a 70 fluid actuated rotary carrier, a reciprocable index pin for intermittently locking said carrier, a series of molding dies carried thereby, a fluid actuated reciprocating molding die coacting with said first named dies successively, means for au- 75

tomatically supplying a charge of material to said series of dies successively, and control means responsive to actuation of said index pin for effecting actuation of both of fluid actuated devices in predetermined sequence.

- 5 9. In a molding press the combination of a rotary carrier, a series of molding dies therein, a reciprocable molding die for coaction with said first named dies successively, means for reciprocating said last named die, means for intermittently rotating said carrier, an index pin movable to intermittently lock said carrier and withdrawable to release the latter, means responsive to withdrawal movement of said pin for effecting 10 actuation of said carrier rotating means, and means responsive to locking movement of said pin for effecting actuation of said last named die.
- 10 15. In a molding press the combination of a carrier rotatable about a substantially horizontal axis, a series of molding dies carried thereby

about said axis, each of said dies comprising separable coacting elements, a reciprocable molding die for coaction with said first named dies successively, and means automatically operable when said first named dies are below said axis 5 to separate the elements thereof to thereby release and discharge the molded blanks by gravity therefrom.

11. In a molding press the combination of coacting molding dies, means for reciprocating one 10 of said dies to effect a working stroke and a return stroke, a movable carrier for the other of said dies, means laterally movable into engagement with said carrier at a predetermined point in the working stroke for holding said dies 15 against separation during a portion of the return stroke, and means responsive to lateral movement of said last named means for terminating the working stroke.

AUGUST F. TOELKE. 20
